[57] **CLAIM**

The ornamental design for a compass, as shown and described.

DESCRIPTION

FIG. 1 is a top plan view of a compass showing the new design;

FIG. 2 is an elevational view of one of the sides of the compass;

FIG. 3 is an elevational view of the other side of the compass;

FIG. 4 is a front elevational view of the compass;

FIG. 5 is a rear elevational view of the compass; and,

FIG. 6 is a bottom plan view of the compass.

The broken line showing is for illustrative purposes only and forms no part of the claimed design.
